UNITED STATES PATENT OFFICE.

CHARLES E. GODLEY, OF DETROIT, MICHIGAN, ASSIGNOR TO EDMUNDS AND JONES CORPORATION, OF DETROIT, MICHIGAN, A CORPORATION OF NEW YORK.

TAIL LAMP.

Application filed November 17, 1922. Serial No. 601,497.

To all whom it may concern:

Be it known that I, CHARLES E. GODLEY, a citizen of the United States, and residing at Detroit, in the county of Wayne and State of Michigan, have invented a new and Improved Tail Lamp, of which the following is a specification.

This invention relates to electric lamps which are usually mounted on the rear ends 10 of motor vehicles to illuminate the license plate and to indicate the presence of the vehicle, and its object is to provide a lamp of this character which may be constructed of a minimum number of parts and at low cost, 15 and which will be dust-proof.

This invention consists in the details of construction illustrated in the accompanying drawing and particularly pointed out in the claim.

20 In the drawing Fig. 1 is a section of this improved tail-lamp on the line 1—1 of Fig. 2. Fig. 2 is a front elevation of the lamp. Fig. 3 is a section on the line 3—3 of Fig. 1.

25 Similar reference characters refer to like parts throughout the several views.

The present lamp consists of a body, a connector sleeve mounted therein and supporting a light bulb, a combined lens and shell of glass extending into the body and closing one end thereof, means to hold the parts together, and means to seal the joint between the inner end of the lamp glass and the end of the body.

30 The body consists of a cylindrical shell 1 of sheet metal having an end 2 in which the thimble 3 is mounted to support the well known connector sleeve 4. A conductor 5 and the base 6 of the bulb 7 extend into this connector. Holes may be formed in this end 2 to receive the screws 8 by means of which the lamp may be attached to any desired support.

35 The lamp glass consists of a tubular portion 10 and an end 11 integral therewith which end may have any desired form, that shown being a dome with circular shoulders on its inner side. The shell 1 of the body is formed with an enlarged outer end 12

terminating in an inwardly inclined flange 13 to receive the locking ring 14 of spring 50 wire which holds the glass in place.

A packing ring 16 of rubber, paper or other suitable material is placed between the end of the tubular portion 10 of the lamp glass and the end 2 of the body and thus 55 effectually seals the lamp and renders it dust proof. The shell 1 has an opening 17 through which light may fall on a license plate in the usual manner. The tongues 18 may be formed adjacent the opening 17 and 60 be bent to engage the glass tube to help position it. To increase the projection of light through the window or opening 17 and also through the lens, I preferably make the shell 1 of the body sufficiently larger in diameter than the tubular glass portion 10 so that a band 19 of light reflecting material 65 may be disposed between them as shown in the drawings. Then I form the shell 1 inwardly at the two longitudinal edges of the 70 said window opening so as to afford inwardly directed tongues having tip portions in flatwise engagement with the tubular glass portion 10. With the tongues thus formed, 75 as shown in Fig. 3, their inwardly directed parts engage the ends of the reflecting band 19 so as to prevent this from moving out of position circumferentially of the lamp body.

At the same time, the tip portions by their engagement with the tubular glass portion 80 10 aid in clamping the shell tightly to this glass portion and prevent dust from entering.

The lamp glass may be molded by placing 85 a small amount of ruby glass in the bottom of a proper mold and a sufficient amount of clear glass upon the ruby glass. A plunger is then forced down to cause the glass to assume the shape shown in the drawing. Or the entire body may be molded of clear 90 glass after which a ruby glaze may be applied to the end thereof.

A lamp glass in which the tubular body portion and the circular end portion are integral avoids the joint that can seldom be 95 made tight except by expensive grinding

and which, unless a packing cushion is used, is liable to become noisy. The circumferential rib 20 at the outer edge of the circular end 11 may be omitted if desired.

5 I claim:—

In a lamp, a glass member comprising in integral formation a lens and a tubular wall portion, a metal shell housing the said wall

portion and having a bore larger than the outside diameter of the said wall portion, the metal shell having a window opening therein, and a light reflecting band disposed between the metal shell and the tubular wall portion, on the side of the lamp opposite the window opening.

CHARLES E. GODLEY.
